UNITED STATES PATENT OFFICE.

CARL A. PETERSON, OF ALDERWOOD MANOR, WASHINGTON.

IRONING MACHINE.

Application filed December 23, 1925. Serial No. 77,193.

This invention relates to improvements in ironing machines and more particularly to a machine of that character designed for use in laundries for ironing shirts; the principal object of the invention being to provide a machine whereby it is possible to iron the neck band, bosom and cuffs of a shirt all at the same time, and in doing so to thereby greatly reduce the time and expense 10 that heretofore was required due to the fact that these were separate operations.

It is also an object of the invention to eliminate the usual leakage at the connections between the iron and its steam supply 15 pipes by a construction in which the iron is stationary and the board is moved against and from it, as distinguished from having the board stationary and the iron movable, as is ordinary practice, with flexible connections with the steam pipes.

Another object of the invention resides in the provision of an adjustable neck band clamp on the ironing board that makes possible a successful use of the same device on 25 shirts having neck bands of different size.

Still further objects reside in the various details of construction and combination of parts that add to the safety, efficiency and ease of operation of the machine.

In accomplishing these and other objects 30 of the invention, I have provided the improved details of construction, the preferred forms of which are illustrated in the accompanying drawings, wherein—

Figure 1 is a side elevation of a shirt ironing machine embodied by the present invention.

Figure 2 is a vertical, sectional view of 40 the upper portion of the machine, showing the construction of the ironing board and its reciprocable and rolling supporting means.

Figure 3 is an end elevation of the machine with certain parts broken away or in section, for better illustration.

Figure 4 is a horizontal sectional view, 45 taken through the machine substantially on line 4—4 in Figure 1.

Figure 5 is a plan view of the ironing board and its base plate showing the adjustable neck band clamp and its actuating quadrant.

Figure 6 is a perspective view of the steam heated iron and the board.

Figure 7 is a perspective view of the belt 55 shifting mechanism and the releasing clutch.

Figure 8 is an elevation of the safety locking means.

Figure 9 is a plan view of the same.

Referring more in detail to the drawings—
The machine comprises a frame structure 60 embodying the parallel, opposite side frames 1 and 2, each with a horizontal top rail 3 and supporting legs 4 joined, adjacent their lower ends, by the connecting pieces 5. The two frames are joined rigidly in spaced relation by the upper and lower connecting bars 6 and 7 at opposite ends of the machine.

Fixed upon the top rails of the side frames, at oppositely disposed points, are 70 standards 8 and 8' provided at their upper ends with bearings 9 within which trunnions 10, projecting from the opposite sides of an ironer 11, are fixed. The ironer is of rectangular form, constructed of metal and 75 has a flat, horizontally disposed under surface 12 against which the pieces to be ironed are pressed for ironing, as will presently be described, and the iron is adapted to be heated by a flow of steam therethrough provided for by the steam supply pipe 13 and exhaust pipe 14 connected with an end thereof.

Disposed within the frame of the machine in substantially a horizontal plane, is a U-shaped member 15 which has the ends of its opposite side members 15'—15" pivotally supported from the legs 4 at one end of the machine by means of a cross rod 16 extended through these ends and through 90 brackets 17 that are fixed to the legs. At its closed end the U-member is adjustably supported through the intermediacy of a wheel 18 threaded onto a vertical, supporting shaft 19, which, at its lower end, is pivotally attached, as at 19' to the lower cross bar 7 and at its upper end extends slidably through a slot 20 in the closed end of the member.

Mounted in bearings 21 and 22 on the 100 side rails of this member 15 is a cross shaft 23 that is disposed centrally below the ironing surface of the ironer 11 and is adapted to be rotated by means of a large gear wheel 25 that is fixed at one end thereof. This gear is driven through a train of gears comprising a small gear 26 rotatable on a stub shaft 27 that is fixed in the side frame and which is fixed to or cast integral with a somewhat larger gear wheel 28 which in turn 110

is driven by a small gear 29 on one end of a driven shaft 30 that is rotatably mounted and extends transversely through the frame and at its opposite end has driving and idler belt wheels 31 and 32 respectively, thereon about which a driven belt 33 is extended.

Mounted within the machine centrally below the ironer is a vertically disposed post 35 provided with a longitudinal slot 36 through which the shaft 23 operates and which permits vertical, longitudinal movement of the post. At its lower end the post is slidably fitted within an opening 37 in a guide plate 38 fixed horizontally between the leg connecting members 5 of the side frames and at its upper end it has a spider frame 39 fixed thereon wherein a pair of rollers 40 are mounted to horizontally support the base plate 41 of the ironing board 42, the ironing board being supported in spaced relation to the base plate through the intermediacy of blocks or posts 43. A pair of angle bars 44 are fixed in parallel relation on the spider frame and serve as guides within which the base plate 41 is movable, it being supported on the rollers for adjustment in the longitudinal direction of the machine from a position beneath the inner end to a position forwardly thereof at the outer end of the guide bars at which position the shirts are placed on or removed from the board.

The ironing board is adapted to be raised against and lowered from the ironing surface 12 of the ironer by vertical reciprocable movement of the post 35, this being effected by a pair of cams 46 that are fixed on the shaft 23 and which operate against rollers 47 supported at the ends of a pin 48 that extends through the post above the shaft. By this construction, each rotation of shaft 23 causes the post to be actuated upwardly to raise the ironing board against the ironing surface 12, and to then lower it to starting position, as shown in dotted and full lines, respectively in Figure 1.

While a shirt is being placed in the ironing board prior to its being moved beneath and then advanced against the ironing surface, the post 35 is in its lowered position and the driving belt 33 operates about the idler wheel 32, then, after the shirt has been placed on the board and the board moved to a position below the ironer and it is desired to start the machine for the purpose of pressing the board against the iron, the operator shifts the belt onto the driving belt wheel 31 so that, through the train of driving gears previously described, the shaft 23 will be revolved and the cams 46 turned therewith so that, by their lifting contact with rollers 47, they lift the post and board. The belt is shifted by downward pressure against a pedal 50 fixed at the end of a shaft 51 supported horizontally in

brackets 52 depending from the lower cross bars 7 at opposite ends of the frame. Fixed to the shaft is an upwardly extending arm 54, which, at its upper end, has pivotal connection with a cross bar 55 that is horizontally slidable in the upper portion of the frame and which at one end has an upwardly and laterally extended arm 56 provided at its end with a loop 57 which encircles the driving belt. A coiled spring 54' is attached to the arm 54 and to the frame of the machine so as to normally retain the bar at such position that the belt is held on the idler wheel, but when the operator presses down on the pedal 50 this rocks the arm 54 so to shift the bar 55 and belt guide to move the belt onto the drive wheel 31.

In order that this driving connection may be retained for a certain length of time after initial action without requiring a continued pressure on the pedal, and to provide for the automatic shifting of the belt to the idler wheel at the instant the ironing board reaches its upper limit of travel against the ironing surface so that it will be held there until the ironing operation is complete, I have fixed on the shaft 23, a clutch collar 58 provided at diametrically opposite sides with notches 59—59' and adjacent thereto, I have mounted rotatably on the shaft, a clutch collar 60 provided with a single tooth 61 that is adapted to seat in either of said notches. Pivotally supported from a bracket 63 fixed to a cross bar 64 in the frame, is a lever 65 provided at one end with a yoke 66 that encloses the collar 61 with pivot pin 67 extended into the same, and at its other end has pivotal connection, as at 68 in Figure 7, with the lever 54, the connection being such that when the lever 54 is shifted laterally by pressure on the foot pedal, which also shifts the belt onto the drive wheel, the lever 65 slides the collar 60 away from collar 58 so that the tooth 61 is unseated from the notch 59. Then as the shaft 23 starts to rotate and collar 58 starts to rotate therewith, the notch 59 moves from registering alignment with the tooth 61 and the latter by its engagement with the adjacent end surface of the collar 58 is prevented from moving back to normal position; thus it is retained "out" until the shaft 23 and collar 58 have been rotated through 180 degrees and the ironing board lifted against the ironing surface, at which time, the tooth 61 snaps back into the next notch 59' due to the tension provided by the spring 54' which acts then to pull the lever 54 back and thus shift the belt back onto the idler wheel. Thus the board remains at its upper position against the ironer. After sufficient time has passed for the article on the board to be ironed, the operator again presses down on the pedal, and this, as previously described, again unseats the tooth 61 of col-

lar 60 from the notch 59' of collar 58 and also shifts the belt onto the driving wheel so that the machine is again driven until the shaft 23 has made another half revolution 5 and the board has been moved to its lower initial position, at which time it is automatically stopped by the movement of the belt shifter permitted by the seating of the tooth 61 in the notch 59.

10 Mounted at one end of the ironing board is an adjustable neck band clamp. This comprises a central block 70 that is so mounted that it may be moved a limited distance longitudinally of the board by means of a 15 shifting bar 71. The bar extends centrally along the under side of the board through guides 72 and with one end turned upwardly through a slot 73 in the board and fixed in the block 70 and its forward end portion turned downwardly through a slot 73' in the base plate and then again extended forwardly to near the forward end of the base plate where it has a stud 74 fixed therein. 20 The stud extends upwardly within an eccentric slot 75 in a quadrant 76 that is pivotally fixed by a pin 77 to the top of the base plate. The quadrant has a handle 78 by means of which it may be shifted so as to adjust the rod rearwardly or forwardly to thereby effect corresponding shifting of the block 70. 25 The forward edge of the block is curved to fit within the front part of a neck band of a shirt and has a notch 79 to receive the base of a collar button for holding the neck band ends together and at its rear edge it has a central projection 80 with outwardly diverging faces 81 and spaced therefrom are outwardly diverging prongs 82 which extend into slots 83 provided in wing blocks 84'-84' 30 adapted to fit within a neck band at opposite sides and which are slidably retained between a flange plate 85 fixed to the rear end of the board and guide rollers 86 mounted on the board at opposite sides of the projection 80. The construction is such that when the block 70 is drawn forwardly by the bar 71, the diverging prongs 81 cause the blocks 84' to be moved apart to thereby draw the neck band tightly about the blocks 35 40 and when the block 70 is shifted back, the wing blocks will again be drawn toward each other to loosen the band. The several blocks may be held in place by an overlying plate 87 mounted on the roller mounting studs.

45 There is provided in the inner end of the ironer 11, a curved recess 11a within which the neck band clamp is adapted to fit when the ironing board is lifted against the ironer so that, with the neck band of a shirt fitted 50 about the clamp and the board lifted to ironing position, the band will be ironed at the same time the piece in the board is ironed.

55 The forward end of the clamp shifting bar 71 has a downturned end 71' which serves to actuate a safety locking device whereby

the machine may be held from operating until all the parts are in proper position. The locking device comprises a bell crank lever 90 supported pivotally from the frame with one arm 91 extended in position to be 5 engaged by the downturned end 71' of the bar 71 and having its other arm 92 extended into holding relation with a pin 93 on a disk 94 fixed to the shaft 30. When the ironing board is shifted inwardly along the guide 75 bars to a position beneath the ironer, the end 71' of the bar 71 engages arm 91 and rocks the lever into position to prevent the shaft from turning, but when the operator turns the quadrant 76 to pull outwardly on the 80 bar 71, so that end 71' is moved forwardly, the bell crank lever is shifted by a spring 96 attached thereto to release the shaft so that the machine may operate.

A roller 98 is mounted by standards 99 85 at the front end of the ironing board across which the lower portion of the shirt is placed, and a crank 100 is provided for turning the roller. The roller has protuberances 90 therein which serve to draw the shirt tight 99 across the top of the board.

For ironing the cuffs of a shirt, I have provided the upwardly projecting blocks 102 at the forward corners of the board over which the cuffs may be fitted and have provided correspondingly shaped sockets 103 in the under side of the ironer into which they will be pressed when the board is moved against the iron.

Assuming that the parts are so constructed, the operation of the device is as follows: The parts of the machine, at the start of an operation are so arranged that the ironing board will be in lowered position and the belt will be operating about the idler wheel. 100 The operator first draws the table 42 outwardly along the guide channels 44 so that it is uncovered by the ironer. He then places the shirt over the board 42 so that the bosom of the shirt is in position to be 105 brought in contact with the ironing surface when the board is lifted. He then fits the neck band of the shirt about the blocks 70, 84'-84' of the neck band clamp and tightens the clamp within the band by movement 110 of segment 76 and then places the cuffs of the shirt over the cuff blocks 102. The bosom of the shirt is drawn tight across the top of the board by pulling the lower part 115 of the shirt across the roller 98 and then rotating it so that its protuberances will catch and hold the shirt tight. The board 42 is then shifted inwardly along the guide channels to a position beneath the ironer.

The operator next presses on pedal 50 to 120 actuate arm 54 to shift the belt to the driving wheel and this starts the shaft 23 to rotating. Shifting of levers 54 also actuates lever 65 to unseat the clutch tooth 61 from the clutch notch 59 and retains the parts in 125

driving position. The cams 46 rotate with the shaft 23 to lift the post 35 to carry the ironing board against the ironer, at which time the driving connection is broken by the shifting of the belt back to the idler wheel incidental to the clutch tooth 61 dropping into the notch 59' in the clutch collar 58, as was previously described. After the shirt has been ironed for a time, the operator again presses on the pedal and the machine is again set in motion and this carries the board downwardly to starting position where it is again automatically stopped. The board may then be drawn forwardly and the shirt removed. Thus, the bosom, neck band and cuffs are all ironed at the same operation.

Having thus described my invention, what I claim as new therein and desire to secure by Letters-Patent, is:

1. In a device of the character described, a frame structure, a heated ironer supported horizontally by the frame, a vertical post supported reciprocally in the frame, centrally beneath the iron, a frame mounted on top of the post comprising a horizontal guideway and rollers therein, an ironing board having a base plate slidable along the guideway on said rollers to position the board directly beneath or at one end of the iron, a horizontal drive shaft, cams on the shaft, rollers on the post engaged by the cams to cause the post to be raised and lowered to actuate the board against and from the ironer, driving mechanism for the shaft including a belt operable over driving and idler wheels, a belt shifter, manually operable means for shifting the belt onto the driving wheel and automatically operable means for shifting it to the idler wheel when the post has been actuated to its upper or to its lower limit of travel.

2. In a device of the character described, a frame structure, a heated ironer supported horizontally by the frame, a vertical post supported reciprocally in the frame centrally beneath the ironer, a frame mounted on top of the post comprising a horizontal guideway and rollers therein, an ironing board having a base plate slidable along the guideway on said rollers to position the board directly beneath or at one end of the ironer, a horizontal drive shaft, cams on the shaft, rollers on the post engaged by the cams to

cause the post to be raised and lowered to 55 actuate the board against and from the ironer, driving mechanism for the shaft including a belt operable over driving and idler wheels, a belt shifter comprising a rock shaft and lever and yieldable means attached to the lever for retaining the belt normally on the idler wheel, a pedal for actuating the rock shaft to shift the belt to the driving wheel, a second lever pivotally mounted between its ends, having one end 60 connected with the lever of the rock shaft, a collar slidable on the driven shaft and connected with the other end of the second lever; said collar having a tooth projecting from one side thereof, a second collar fixed 70 on the driven shaft adapted to be engaged by the said tooth to retain the parts in position for driving and having notches therein at diametrically opposite points to receive the tooth when the post has been lifted to 75 its upper or to its lower limit of movement so as to permit shifting of the belt to the idler wheel.

3. In an ironing device of the character described, an ironer provided with a flat 80 ironing surface and having upwardly formed sockets in one end, an ironing board adapted to be moved from and against the ironing surface and having upwardly extending blocks at one end over which the cuffs of a 85 shirt that is placed on the board may be fitted, said blocks being adapted, when the board is raised against the ironer, to fit within the sockets of the ironer.

4. In an ironing device of the character 90 described, an ironer provided with a flat ironing surface on its under side and having a curved recess in one end and a pair of upwardly formed sockets at its opposite end, an ironing board movable from and against 95 the ironing surface having a collar band clamp at one end about which the neck band of a shirt may be fitted and having upwardly projecting blocks at its other end over which the cuffs of the shirt may be 100 fitted; said clamp and blocks being adapted, when the board is raised against the iron, to seat, respectively, within the curved recess and the sockets.

Signed at Everett, Snohomish County, 105 Washington, this 2nd day of November, 1925.

CARL A. PETERSON.
